UNITED STATES PATENT OFFICE.

ABE MASKOW, OF BROOKLYN, NEW YORK.

PICTURE-CORD HOOK AND ORNAMENT.

Application filed June 24, 1925. Serial No. 39,327.

My invention relates to improved picture hooks in which an ornament, picture hook, tassel and cord are united into a new article of manufacture and it is my object to produce an ornament (which covers and hides the picture hook) of metal or other suitable rigid material to which the hook proper is permanently and rigidly secured and to which the picture cord and tassel may be secured. Heretofore the ornament has been made of fabric and the hoop proper has been sewed to it. This has proved unsatisfactory as the sewing gives way and the ornament falls off exposing the unsightly hook, sometimes before the device can reach the user. The fabric ornaments also collected dust and dirt and rapidly deteriorated and looked unsightly after a short time. My invention is intended to overcome these defects with a device which is simple and cheap to make and which can be easily assembled.

In the drawing Fig. 1 is a back view of my improved device; Fig. 2 a side view of the ornament and hook of Fig. 1, with the ornament partly broken away; and Fig. 3 a sectional view of a portion of the structure of Fig. 1 on the line 3—3 thereof. Figure 4 is a view partly in section and showing another position of the loop with relation to the hook.

The device consists of an ornament 1, of metal or any other suitable material, and may be of any size, shape or ornamental design, so long as it covers and hides the hook proper. The picture hook proper 2 is permanently secured to the back of the ornament in any suitable manner, solder 3 being preferably used for this purpose. The eye 2' is hingedly secured to the hook 2 and may be swung in against the ornament when the hook is used on a moulding or swung out when the loop is used on a nail, screw or other device or when the hook is used on a moulding and the loop is conjointly used on a nail or the like. A picture cord 4 is passed through the hook 2 and a tassel 5 is hung from the hook by a cord 6, with a button 7 connecting the tassel and cord. This button is preferably made of wood or other hard material and is painted or lacquered so that it will always present a good appearance. The fabric or cord covered buttons heretofore used quickly frayed and exposed the wood, presenting an untidy appearance.

The device of my invention is a perma-

nently assembled ornament, hook, cord and tassel which will retain an attractive appearance for a long time and which can be easily and cheaply made and assembled. It will be noted upon inspection of the drawing that the hook 2 is formed with spaced eyes 7 which are permanently secured to the ornamental wall plate 1, while the loop 2' is formed with similar eyes 8 which are arranged between and frictionally engaged by the eyes 7 of the hook 2. The loop is thus supported for pivotal movement with relation to the hook 2, so that it can occupy either the position illustrated in Figure 3 or the position illustrated in Figure 4. The eyes 8 of the loop 2 are also arranged substantially in alignment with the eyes 7 of the hook 2 to receive the picture cord 4 which passes through all of said eyes as clearly illustrated. The loop 2' is therefore permitted to pivot about the picture cord as will be readily understood, the cord holding the loop against casual separation from the hook when used as an additional supporting means for the picture.

While it is believed that from the foregoing description the nature and advantages of the invention will be readily understood, I desire to have it known that I do not limit myself to what is herein shown and described, and that such changes may be resorted to when desired as fall within the scope of what is claimed.

I claim:

1. In combination, an ornamental wall plate, supporting means carried on the back of the plate for suspending the latter from the wall, additional supporting means pivotally mounted on the first mentioned means, both of said means being wholly concealed by the plate when on the wall, and each of said means being designed to receive and support a picture cord.

2. As a new article of manufacture, a combined ornament and picture hook comprising a rigid plate-like ornament, a hook rigidly secured to the back of the ornament and adapted to engage a wall moulding, a loop pivotally secured to the hook on the back of the ornament and adapted to engage a nail, screw or hook in a wall, said hook and loop being also adapted to support a picture cord, said ornament completely covering and concealing the hook and loop when on the wall.

3. In combination, an ornamental wall

plate, a supporting hook rigidly secured to the back of said plate and adapted to engage a wall moulding, spaced eyes formed on said hook and adapted to receive a picture cord, and an additional supporting loop arranged between said eyes and pivotally mounted about said cord.

4. In combination, an ornamental wall plate, a hook rigidly secured to the back of said plate and adapted to engage a wall moulding, spaced eyes formed on said hook

and adapted to receive a picture cord, a supporting loop formed with spaced eyes arranged between and frictionally engaged by the eyes of said loop, and substantially 15 aligned with the latter to receive said cord, said hook and loop being wholly concealed by the plate when on the wall.

In testimony whereof I have affixed my signature.

ABE MASKOW.
